UNITED STATES PATENT OFFICE.

DAVID HARRISON SHERIFF, JR., OF KANSAS CITY, MISSOURI.

RHEOSTAT WITH AUXILIARY CONTACT SYSTEM.

Application filed December 4, 1922. Serial No. 604,820.

To all whom it may concern:

Be it known that I, DAVID H. SHERIFF, Jr., a citizen of the United States, residing at Kansas City, in the county of Jackson and State of Missouri, have invented a new and Improved Rheostat with Auxiliary Contact Systems, of which the following is a specification.

My invention relates to certain new and useful improvements in rheostats of the kind especially designed for use in radio sets and the invention particularly has for its object to provide means in connection with the rheostat for connecting one or more meters in the circuit while manipulating the rheostat in adjusting the resistance in the circuit; to provide a means whereby one set of meters may serve any number of rheostat sets that may be used, without interference 20 between the several rheostat sets and the bulbs controlled thereby.

In its general nature, the invention resides in providing a rheostat of the rotary spindle type with a set of auxiliary contacts designed to be controlled by the movement of the rheostat spindle, particularly while adjusting the resistance.

In its more detail nature, the invention includes a rheostat having a spindle and knob 30 adapted to be turned to cut in or out an amount of resistance connected in the circuit and provided with a set of auxiliary contacts whereby while the rheostat spindle may be turned for varying the resistance, the 35 auxiliary contacts may be simultaneously controlled, substantially automatically, by the operator to cut in either a volt meter or ammeter, or both, so that the current flowing through the bulb and the voltage at the 40 bulb terminals may be indicated to the operator, the arrangement of auxiliary contacts being such, and they being so combined with the rheostat, that one set of meters can be used with any number of sets of rheostats 45 so that if there are a plurality of bulbs in circuit each with their separate rheostat controls, the operator need only provide a single set of meters in order to cooperate with all of the rheostats and without the necessity of 50 changing any wire terminal connections between the meters and the line circuits, or, in other words, one set of meters is permanently wired up with all of the rheostats but separately responsive to each rheostat manipulation.

In its more specific nature, the invention

resides in those novel details of construction, combination and arrangement of parts, all of which will be first fully explained, then be specifically pointed out in the appended 60 claims and illustrated in the accompanying drawings, in which:

Figure 1 is a rear view of a rheostat of the rotary type embodying my invention.

Figure 2 is a vertical central longitudinal 65 section of the same, parts being shown in elevation.

Figure 3 is a modification of the rheostat shown in Figures 1 and 2.

Figures 4, 5 and 6 are circuit diagrams 70 showing how a plurality of rheostats are connected up with one set of meters and indicating the paths of current with different adjustments of the rheostat.

Figure 7 is a vertical section, somewhat 75 diagrammatic, showing how the invention may be applied to rheostats of that type wherein the resistance coil is mounted on the dial and turns with the same.

Figure 8 is a vertical section showing how 80 the invention may be applied to rheostats of the compression type.

In the drawings, in which like numerals and letters of reference designate like parts in all of the figures, 1 is the panel to which 85 the insulated block or base 2 of the rheostat and the dial 11 thereof are secured in any usual way. 3 is the resistance block which is mounted on the insulating base 2 and on 90 which is wound the resistance wire 4, one end of which is connected to the terminal post 5, as shown. 6 is the contact spring finger whose hub 7 is secured in any suitable way to the rotatable spindle 8, which is 95 adapted to be turned on its axis by the knob 9. The latter may carry a pointer 10 to cooperate with the dial 11. All of the foregoing parts are of the ordinary construction except that with my arrangement the spindle 100 8 has axial or longitudinal movement as well as rotary movement, the longitudinal movement being limited by a suitable stop 21 in one direction and by the knob 9 in the other direction.

In carrying out my invention, I provide 105 one or more auxiliary contact fingers mounted on the insulating base 2 and having their contact ends projected to cooperate with a disk 12 on the spindle 8, the disk 12 in the preferred embodiment of the invention being rigidly mounted on the spindle and in 110 electrical contact therewith.

In the preferred embodiment of the invention, I provide four auxiliary contact fingers, numbered 13, 14, 15, 16, respectively, in the drawings, and secured to contact posts 5 17, 18, 19, 20, respectively, as shown in Figures 1 and 2 of the drawings. These auxiliary contact fingers have their contacting ends projected over one another as shown in Figure 1, but not in electrical connection 10 with one another, and contact fingers 14, 15 are united at the projecting ends by an insulating block 28 which causes the fingers 14, 15 to move in unison in a manner presently explained.

15 In the practical arrangement of this embodiment of the invention, the disk 12 and contact finger 13 are normally in electrical engagement (see Figure 2) and are held normally in such engagement by the resiliency 20 of the finger 6, which tends to pull the spindle 8 from right to left in Figure 2. When, however, the spindle 8 is pulled outwardly from left to right in Figure 2, the disk 12 will disengage the contact point of 25 the finger 13 and engage the contact point of the finger 14, thus shifting the circuit at the disk 12 from the contact 13 to the contact 14. Further movement from left to right in Figure 2 causes contacts 14, 15 to 30 be pushed over from left to right in Figure 2 until the contact points of fingers 15, 16 are in engagement.

In my embodiment of the invention illustrated in Figure 3, the contact fingers 13^a to 35 16^a, inclusive, are reversed and normally the spindle 8 is held in its right hand extremity of movement by a spring 22 which overcomes the tension of the spring 6 but when the knob is pushed inwardly, the disk 12 will 40 disengage the contact point 13^a and engage that of the finger 14^a and on further movement cause the contact points of fingers 15^a, 16^a to be brought together. As best shown 45 in Figure 3, the parts 19^a, 20^a correspond to the parts 19 and 20 in Figure 1.

In using my invention, all of the contact points 13, 14, 15, 16 may be used or only one or more, as desired. When the system on which the rheostat is to be used includes a 50 bulb 23 and a volt meter V and an ammeter A, all of the auxiliary contacts are used, as shown, for example in Figures 4, 5 and 6, by reference to which it will be seen that one of the line wires connects directly to the bulb 23 and to the volt meter, the other line wire connecting to the terminal 17 while the other terminal of the bulb 23 connects to the terminals 5 and 20. The other terminal of the volt ammeter connects to terminal 19 and the other terminal of the ammeter connects to terminal 18. When two or 55 more bulbs and rheostats are employed in the circuit, terminals 17 of each rheostat are connected together, terminals 18 are connected 60 together, terminals 19 are connected

together but terminals 20 and 5 are individually connected with their respective bulbs.

Assume the diagram shown in Figure 4 having been adjusted as indicated, the normal circuit connection from the resistance is 70 made through the finger 6 and disk 12 to the contact finger which is carried by the terminal 17, with the result that the current flows through the bulb, through the resistance cut in, through the contact finger 6, 75 disk 12, finger 13 and terminal 17. Should the operator desire to adjust the resistance and at the same time get an ammeter reading, he merely pulls out on the knob (if the embodiment shown in Figures 1 and 2 is 80 used) or pushes in on the knob 9 (if the embodiment shown in Figure 3 is used) to move the disk 12 out of contact with the finger 13 which thereby opens the circuit at terminal 17, (see right hand rheostat, Figure 85 5) and closes the circuit with contact 14, thus causing the current to flow to contact 18 and through the ammeter, as indicated in Figure 5, the right hand rheostat being the one under adjustment in the present consideration. 90

Now, assume the operator wishes to get a volt reading and an ammeter reading both, he moves the spindle 8 to the complete limit of its movement against the tension of the 95 spring to open the circuit between the spindle disk 12 and the contact finger 13 and its terminal 17 and closes the circuit with the contact finger 14 and its terminal 18 and at the same time closes the circuit between the fingers 15 and 16, which produces a current over terminals 19 and 20, thereby cutting in the volt meter, as well as the ammeter, as shown in the left hand unit in Figure 6. In this way, he can obtain the reading of both 100 the voltage and current passing through the bulb 23 of the particular unit under adjustment. Of course, if only an ammeter is used, the contacts which control the volt meter may be omitted, and vice versa. 110

In Figure 7 I have illustrated the manner in which my invention may be applied to those rheostats in which the resistance coil is rotatable and the contact finger stationary. In this figure those parts corresponding to 115 similar parts in the preceding figures bear the same reference characters plus the index letter "x", as 1^x, 4^x, etc. In this embodiment of the invention the dial 11^x turns with the spindle 8^x to vary the resistance. The spindle 8^x is pushed in or pulled out to change the relation of the disk 12^x with the auxiliary contacts 13^x, 14^x, 15^x and 16^x as in the preceding embodiment illustrated and described herein. 120

Figure 8 shows the embodiment of my invention, adapting it to rheostats of the compression type. In this figure those parts which functionally correspond with similar parts in the preceding figures bear the same 130

numbers as in the preceding figures plus the index letter "y," as 1^y, 4^y, 5^y, etc. The resistance element 4^y is compressible between a stationary plate 5^y and a movable plate 6^y on 5 a screw 25 threaded into the boxing 24 and having a squared end 26 slidably socketed at 27 into the end of the spindle 8^y so that by turning the spindle the resistance may be varied. By pushing in or pulling out the 10 spindle the relation of the disks 12^y to the auxiliary contacts 13^y, 14^y, 15^y and 16^y may be varied as desired, in the same way as in the preceding embodiments.

The essential feature of my invention 15 resides in combining with a rheostat an auxiliary contact system useful for cutting in circuits or circuit branches while manipulating the resistance adjustment of a circuit.

While I have shown but two embodiments 20 of the invention I desire it understood that modifications in the details of construction, combination and arrangement of parts may be readily made without departing from the spirit of the invention or the scope of the 25 appended claims.

What I claim is:

1. In a rheostat wherein is provided a 30 rotary spindle and means cooperating therewith for varying the resistance in circuit; a set of auxiliary contacts, and means bringing the same into action.

2. In a rheostat wherein is provided a 35 rotary spindle and means cooperating therewith for varying the resistance in circuit; a set of auxiliary contacts, and an element on said spindle cooperating with said auxiliary contacts for the purposes described.

3. In a rheostat wherein is provided a 40 resistance element and a rotary spindle with contact finger riding over said resistance element; a set of auxiliary contacts, and means on said spindle adapted on axial movement of said spindle to cooperate with said auxiliary contacts.

4. In a rheostat wherein is provided a 45 rotary spindle, a stationary resistance element, and a spring contact finger carried by said spindle for engaging said resistance element to vary the resistance in circuit; of an auxiliary contact finger, a disk on said spindle normally engaging said auxiliary contact finger, a second auxiliary contact finger spaced from said disk, said spindle being longitudinally movable whereby said disk may be disengaged from the first auxiliary contact finger and engaged with the 50 said second auxiliary contact finger, substantially as shown and described.

5. In a rheostat wherein is provided a 55 rotary spindle, a stationary resistance ele-

ment, and a spring contact finger carried by said spindle for engaging said resistance element to vary the resistance in circuit; of an auxiliary contact finger, a disk on said spindle normally engaging said auxiliary contact finger, a second auxiliary contact finger spaced from said disk, said spindle being longitudinally movable whereby said disk may be disengaged from the first auxiliary contact finger and engaged with the 60 said second auxiliary contact finger, a third auxiliary contact finger, an insulating medium between the second and third auxiliary contact finger, and a fourth auxiliary contact finger cooperative with the third auxiliary contact finger to close a circuit upon further movement of said spindle to push said second and third contact fingers over.

6. In an apparatus of the character stated, a line circuit, a plurality of rheostats and 65 bulbs controlled thereby connected with said line circuit, a single set of meters, and means on each of said rheostats and electrically connected with said meters whereby the manipulations of the movable element 70 of the rheostat may be caused to connect that particular rheostat and the bulb controlled thereby in circuit with said meters.

7. In an apparatus of the character 75 stated, a line circuit, a plurality of rheostats and bulbs controlled thereby connected to said line circuit, a single set of meters and cooperative connections and mechanisms between said meters and the several rheostats whereby at least one of said meters 80 may be electrically connected to the bulb circuit of any rheostat by manipulation of the rheostat adjustment element.

8. In a rheostat wherein is provided a 85 rotary spindle, a resistance element, a spring contact finger for engaging with said resistance element to vary the resistance in circuit; of an auxiliary contact finger, a disk on said spindle movably engaging said auxiliary contact finger, said disk being axially 90 movable to engage and disengage said auxiliary contact finger.

9. In a rheostat wherein is provided a 95 rotary spindle, a resistance element, a spring contact finger for engaging with said resistance element to vary the resistance in circuit; of an auxiliary contact finger, a disk on said spindle movably engaging said auxiliary contact finger, said disk being axially 100 movable to engage and disengage said auxiliary contact finger, and other auxiliary contact fingers adapted to be controlled by the movements of said disk.

DAVID HARRISON SHERIFF, JR.
